PORTABLE TELEVISION RECEIVING SET SUPPORT FOR AUTOMOBILES

Walter P. Myers, River Forest, Ill., and Joseph J. Orlof,
Wheaton, Ill. (both of 2958 W. Carroll Ave., Chicago,
Ill. 60612)

Filed May 31, 1966, Ser. No. 2,471

Term of patent 14 years

(Cl. D14—6)

FIGURE 1 is a perspective view of our new design of a portable television receiving set support for automobiles showing it installed in an automobile body between the back of the front seat and the back of the rear seat thereof, portions of the automobile body front and rear seats being fragmentally shown in dotted lines;

FIGURE 2 is an enlarged perspective view of the support; and

FIGURE 3 is an end elevation of the same looking toward its normally rearward end.

The dotted lines showing in the drawings of the automobile body front and rear seats are effected for the purposes of illustration only.

We claim:

The ornamental design for a portable television receiving set support for automobiles, substantially as shown and described.
